UNITED STATES PATENT OFFICE.

THURE DAHL, OF NEW YORK, N. Y., ASSIGNOR TO CORONA CORPORATION, OF NEW YORK, N. Y., A CORPORATION OF NEW YORK.

LAMP-SHADE HOLDER.

Application filed February 10, 1925. Serial No. 8,153.

My present invention is primarily concerned with means for readily attaching a lamp shade of any desired character to a conventional type of lamp socket.

5 Lamp sockets as conventionally constructed, are equipped with a few external threads spaced a short distance from the open socket end of the shell, upon which a collar is to be threaded which serves to 10 mount the shade. Inasmuch as the shell is usually substantially enclosed by a decorative socket cover member, the shade supporting member is attached by reaching the hand inside of the lamp shade and attempting 15 the threading operation, which even under the most advantageous conditions, involves preliminary groping to bring the threads into registry, followed by a prolonged threading operation to screw the 20 holder home. It is especially difficult to perform the turning or screwing operation within the shade of small diameter. Furthermore, unless the thread on the shade holder matches precisely that on the socket, 25 which in practice, is frequently not the case, and is correctly entered thereon the parts may jam in the attempt to couple said members, and forcible rotation either to screw 30 home or to remove the holder preparatory to a renewed attempt to couple it may result in twisting the socket leads with the 35 danger of a short circuit.

It is among the objects of my invention to overcome all of the above noted difficulties without complicating the construction, 40 or adding to its cost, or detracting from the security of attachment and without interfering with ready removal of the shade holder from the socket.

45 In a preferred embodiment of the invention, the metallic shade supporting collar, in addition to being screw threaded is provided with a number of longitudinal slits, determining spring fingers, yielding sufficiently to permit thrusting the split sleeve over the exterior threads of the socket. The socket is thus firmly gripped by the spring fingers, the threads on which will naturally enter into mating relationship with those on the 50 socket. If desired, the shade holding collar may then be given a short turn for further security of attachment.

55 Although various types of shade holders may be coupled to a socket in this manner, I prefer to use a holder having a shade sup-

porting flange which presses the inner rim of the shade adjacent the socket cover.

In the accompanying drawings in which is shown one of various possible embodiments of the several features of the invention,

60 Figure 1 is a disassembled view in longitudinal section through a socket, socket cover, shade holder and shade.

Figure 2 is a similar view showing the 65 parts assembled and

Figure 3 is a top plan view of the shade supporting member.

In the drawings, I have used the reference letter A to indicate a lamp shell of conventional construction. It may be housed within a conventional socket cover B of general bell shape. The lamp shade supporting member is shown at C, the shade at 70 D, and the lamp bulb at E.

75 More specifically, the socket member or socket shell A is formed at its closed end with a threaded nipple 10 into which screws a hollow plug 11 to retain socket cover B in place, the outlet wires from electrical terminals, in the socket (not shown) being led to a suitable source of current from the plug. The usual screw threads 12 are provided on the exterior of the shell A. The shade supporting member C is of thin readily bendable spring metal such as brass, including a cylindrical collar portion 15 adapted to encircle the shell A and an external trough like flange portion 16 adapted to receive and support the inwardly turned flange 17 at the 80 inner end of the lamp shade. The collar portion 15 of the lamp shade holder is provided with a plurality of longitudinal slits 18 extending from its free end to the flange end thereby determining longitudinal spring 85 fingers which will readily flex outwardly as the collar is thrust over the shell, the threads on the spring fingers ratcheting over the shell threads and mating therewith.

90 The manner of assembling the device is to engage the flange of the shade holder with the flange of the shade, insert the hand within the shade and thrust the collar over the lamp shell or socket A. For enhanced security the shell holding collar may be given 95 a short turn or screw feed over the socket threads.

100 In assembled relationship, as shown in Fig. 2, the flange 17 of the shade is firmly clamped against vibration between the 110

flange 16 of the member C and the rim 20 of the socket cover B.

It will be noted that my invention involves no change in the conventional construction of shade holders other than the provision of a few slits which can be introduced substantially without added cost. Even though the collar threads fit only approximately those of the socket, secure connection is effected by a single thrust eliminating the need for groping to align the threads or the awkward turning of the shade holder through many revolutions, as required in constructions devoid of the slits.

15 It will thus be seen that there is herein described apparatus in which the several features of this invention are embodied, and which apparatus in its action attains the various objects of the invention and is well suited to meet the requirements of practical use.

20 As many changes could be made in the above description and many apparently widely different embodiments of this invention could be made without departing from the scope thereof, it is intended that all matter shown or described in the above shall be interpreted as illustrative and not in a limiting sense.

25 30 Having thus described my invention, what I claim as new and desire to secure by Letters Patent is:—

1. The combination with a lamp socket shell of the type having threads on the exterior thereof, of a metallic lamp shade holder including a threaded collar portion adapted to engage with the threads of the

shell, said collar portion being longitudinally split to define a plurality of spring sections whereby it may be forced into place 40 on the shell by a direct thrust, said holder having a flange for sustaining the weight of a shade with its rim resting on the flange.

2. The combination with a lamp socket shell of the type having exterior threads 45 thereon, of a lamp shade holder including a lamp shade supporting part and a threaded collar portion adapted to mate with the threads on the shell, said collar comprising a plurality of spring sections permitting a 50 thrust fit over the shell.

3. The combination with a lamp socket of the type having threads on its exterior, of a lamp shade holder including a threaded cylindrical portion having a plurality of 55 longitudinal slits therein and including a shade clamping flange, said cylindrical member being adapted for engagement with the exterior of the shell by direct thrust and adapted to be further tightened by rotation.

4. The combination with a lamp socket of the type having exterior threads thereon, a cover therefor, a lamp shade holder including a threaded metallic collar portion longitudinally split to permit direct thrust thereof over the threaded exterior of the socket and a lamp shade supporting flange unitary with the collar to sustain a lamp shade and clamp it against the rim of the socket cover. 70

Signed at New York city, in the county of New York and State of New York, this 30th day of January A. D. 1925.
